CLAIM

The ornamental design for an access control interface, as shown and described.

DESCRIPTION

FIG. 1 is a front right-side perspective illustration of an access control interface showing our new design;

FIG. 2 is a front elevational view thereof;

FIG. 3 is a right-side elevational view thereof, the left-side (not shown) being a mirror image thereof;

FIG. 4 is a top plan view thereof;

FIG. 5 is a bottom view thereof; and,

FIG. 6 is a rear elevational view thereof which is provided for illustrative purposes only and forms no part of the claimed design.
